EDMUND GALE JEWETT, OF BROOKLYN, NEW YORK.

BASEBALL GAME.

Application filed February 3, 1928. Serial No. 251,531.

My invention relates to games which are simulations of outdoor games such as for ball polo, soccer, lacrosse, hockey, or baseball or the like and played indoors upon game boards. My invention is particularly adapted to a baseball game and will be described as such although it may be applied to any other game.

In the usual baseball games the play is upon a game board and the two sides are simulated by one person representing the players or team in the field and another person representing the players at bat, the two alternating for each inning. As the game is usually played a ball is rolled or propelled down a board by one person while the other person attempts to knock or strike the ball with a miniature bat somewhat as in actual play. Games of this type are usually one-sided, i. e. it is usually difficult for one person to compete against the other for the reason that the game boards are so constructed that the difficulties of the person batting are much greater than the other team or vice versa. It is the purpose of my invention, therefore, to provide a simulated baseball game which is dependent upon the skill of the player and in which the difficulties of the two teams are equalized to a great extent whereby the two persons or teams playing have more nearly equal possibilities.

To accomplish this I provide a plurality of playing boards one or more of which may be simultaneously operated by each team each board having thereon movable members representing the ball and the players. I lay one of these boards out in the form of a baseball diamond and provide designations thereon such as a pocket or recess at each of the customary positions of the players of a baseball team. This board represents the players in the field and is to be used by the person or player representing that team. A second board is provided and has designations thereon such as recesses or pockets arranged similar to the bases of a baseball diamond. For the movable members representing the ball and the players I may use balls, such as steel balls. The person operating the first mentioned board moves the board so as to propel the steel ball thereon in a manner simulating the movements of an actual baseball. The player using the second board at the same time manipulates this board in such a manner as to propel a ball thereon in the manner of a runner traversing the bases of the diamond.

My invention will be described with more particularity with reference to the drawings in which:

Fig. 1 is a perspective of the board and a ball thereon to be used by the person representing the team in the field, and

Fig. 2, is a perspective view of a playing board and a ball thereon to be utilized by the team at bat.

As shown in the drawing, I have found it to be practicable to form my playing boards of flat square boards 1 surrounded by a raised molding 2. In the board to be utilized by the team in the field I form substantially semi-spherical depressions 3 arranged in the formation of the positions of the players of a team in the field. I also provide a depression 4 at approximately the position of the home plate. I also cut a slight trough 5 extending from the catcher's position where it is deepest, to a point slightly in front of the home plate. Another depression 6 may be cut into the surface of the playing board alongside the catcher's position to indicate a foul ball or an out pocket to catch a runner coming from third base to home. Upon this board I preferably use a small steel ball as a representation of the baseball.

The second board manipulated by the person representing the team at bat is similar to the first mentioned board except that it has depressions 7 arranged therein in the formation of the bases of a baseball diamond. Alongside of each of these depressions are formed a small auxiliary depression 8 for reasons to be later explained. Upon this board I preferably use a larger steel ball to represent a player running the bases.

When playing the game the person representing the team in the field takes the board shown in Fig. 1 in his hands, places a ball in the recess marked P and endeavors to manipulate the board by tilting, jarring or shaking, to cause the ball to roll toward the depression marked C or catcher's position. If the ball during its travel is arrested and retained in the depression representing the home plate HP it is regarded as a hit. The person representing the team at the bat and having the board shown in Fig. 2 in his hand, places a steel ball in the smaller depression 8 alongside of the home plate pocket and exclaims where he desires the hit to be. For instance, he may call a fly to center field. Immediately upon calling his hit he will endeavor to manipulate his board to propel the

ball toward first base and thence around the bases in proper sequence. The person manipulating the other board simultaneously endeavors to tilt his board to cause the ball 5 representing the baseball to travel toward the recess marked CF. If he manages to get the ball in this pocket before the other player gets the runner into the pocket representing first base it is an "out" or if the person playing 10 the runner gets to first base first he is "safe." Should the small steel ball drop into the depression marked C by the player manipulating the board shown in Fig. 1, it would be a "strike" whereas if the ball travels 15 to the rear of the board without either falling into depression HP or C, it is a ball. Should the ball roll into the depression 6 it may be considered a "foul," a "foul strike" or a "foul fly" caught by one of the players and so 20 considered an "out" or this depression may be utilized as an out pocket to catch a runner coming from third base to home. Any rules may be mutually agreed upon which cause the 25 game to simulate more closely the actual outdoor sport. For instance, a third person may be designated as an umpire to decide doubtful situations. The person representing the runner may call that he intends to steal a 30 base and having a man on one of the bases, place the ball in the slight recess adjacent thereto and proceed to manipulate the board to cause the ball to roll to the next succeeding base. The person using the other board 35 then attempts to manipulate the board to cause the ball thereon to roll to the base on that board similar to the base which the runner is attempting to gain.

It is obvious that slight modifications may 40 be made differing from the boards as illustrated to adapt the boards to other games without departing from the spirit and scope of the invention as defined in the claims appended hereto. I have used the term "ball 45 game" to include any game in which there are opposing sides and in which the object is to manipulate any given vehicle or players or both in a prescribed manner.

I claim:

1. In a simulated baseball game, a pair of 50 game boards one thereof having designations thereon representing the team in the field and one thereof having designations thereon representing the team at bat, movable members representing the baseball and the players 55 adapted to be moved by gravity over said boards said boards being adapted to be used substantially simultaneously by the persons representing the opposing sides to cause said members to simulate the action of a baseball 60 game.

2. In a simulated baseball game, a pair of game boards one of which represents the

team in the field and one of which represents the team at bat, members thereon representing the baseball and the players movable by 65 gravity, depressions in one board arranged in the order of players of a team, depressions in the other of said boards arranged in the order of the bases, said depressions being adapted to arrest the movements of said members, said boards being adapted to be used substantially simultaneously by the persons representing the opposing sides to cause said members to simulate the play of a baseball 70 game. 75

3. In a simulated baseball game a pair of game boards one of which represents the team in the field and one of which represents the team at bat, members thereon representing the baseball and the players movable by 80 gravity, depressions in one board arranged in the order of players of a team, depressions in the other of said boards arranged in the order of the bases, and auxiliary depressions of lesser depth in said latter board disposed adjacent said latter depressions to afford starting positions, all of said depressions being of such depth to arrest the movements of said members, said boards being adapted to be used substantially simultaneously by the persons representing the opposing sides to cause said members to simulate the action of a baseball 85 game. 90

4. In a simulated ball game, a plurality of game boards adapted to be simultaneously 95 utilized by a plurality of persons representing the opposing sides to simulate a ball game, one of said boards having designations thereon arranged in the order of the stations to which the ball is to be manipulated, and another of said boards having designations thereon arranged in the order of the stations of the players and members representing the ball and the players movable over said boards. 100

5. In a simulated baseball game a pair of game boards, movable members thereon representing the baseball and the players, one of said boards representing the team in the field and having depressions therein to arrest the movement of said members, said depressions being arranged in the positions of the players of a team, the other of said boards representing the team at bat and having depressions therein representing the positions of the ball in play, said boards being adapted to be used substantially simultaneously by the persons representing the opposing sides to cause said members to simulate the play of a baseball 110 game. 115

In witness whereof, I hereunto subscribe my signature.

EDMUND GALE JEWETT.
